ATTORNEY

UNITED STATES PATENT OFFICE.

ALBERTO M. ALVARADO, OF DURANGO, MEXICO.

VIOLIN BRIDGE.

Application filed December 8, 1924. Serial No. 754,631.

This invention relates to attachments for stringed instruments, particularly to bridges, and has for its object the provision of a novel bridge designed primarily for use as an auxiliary to the ordinary bridge employed with a violin or other stringed instrument, the auxiliary bridge being located adjacent the ordinary bridge and acting to improve the quality of the music inasmuch as it will give the tones of the instrument a greater degree of sweetness, volume and clearness.

An important object is the provision of an auxiliary bridge of this character which is so constructed and arranged as to be used in conjunction with the ordinary bridge and mounted in slightly spaced relation thereto, the auxiliary bridge itself being of peculiar construction whereby to have the desired effect upon the tones.

An additional object is the provision of a device of this character which will be simple and inexpensive in manufacture, positive in action, efficient and durable in service, and a general improvement in the art.

With the above and other objects and advantages in view, the invention consists in the details of construction to be hereinafter more fully described and claimed and illustrated in the accompanying drawings, in which:

Figure 1 is a plan view of a violin equipped with my auxiliary bridge, and

Figure 2 is a perspective view of the invention alone.

Referring more particularly to the drawings, the letter A designates an ordinary violin having the usual body or sounding board B, neck C, tail piece D, strings E, connected with the tail piece and with the usual tuning keys F, or pegs as they may be called, while the letter G represents the ordinary bridge over which the strings pass. In carrying out the present invention I provide an auxiliary bridge device designated broadly by the numeral 10, which bridge is of substantially the same size and shape as the ordinary bridge G and constructed of the usual material, ordinarily wood. At its lower edge this auxiliary bridge 10 is cut away as indicated at 11 to provide bearing feet 12 engaging upon the sounding board of the violin, and at points spaced inwardly from the side edges the auxiliary bridge is

formed with curved openings 13 with which communicate elongated slots 14 opening out at the edges. At the center of the upper portion there is preferably provided a curved opening 15 as clearly indicated.

One of the essential features in the construction of this auxiliary bridge is the formation of a pair of grooves 16 which lead upwardly from the opening 13 and which gradually increase in width as they progress upwardly, these grooves extending substantially one half the thickness of the body of the bridge as clearly indicated. The top surface of this auxiliary bridge is formed with a plurality of notches 17 similar to those provided in the ordinary bridge and designed for the purpose of having the strings E engaged therein. The auxiliary bridge is engaged upon the sounding board of the violin at a point spaced slightly from the ordinary bridge B which forms part of the original equipment and it will be apparent that the strings will be supported at two slightly spaced points. In actual practice I have discovered that by employment of this auxiliary bridge the quality of the tone produced by the instrument is greatly improved especially in points of sweetness and clearness. The thinning away of the material resulting from the formation of the groove renders the bridge more sensitive to the vibrations of the strings and these vibrations are consequently transmitted to the body or sounding board of the instrument in a more intense manner than is ordinarily the case so that the tones produced will be clearer than is ordinarily possible.

From the foregoing description and a study of the drawings it will be apparent that I have thus provided a very simply constructed and inexpensive device or attachment for the purpose specified which will efficiently perform all the functions for which it is intended.

While I have shown and described the preferred embodiment of the invention, it should be understood that I reserve the right to make such changes in the form, construction and arrangement of parts as will not depart from the spirit of the invention or the scope of the subjoined claim.

Having thus described the invention, I claim:

A violin bridge comprising a flat body

having its lower edge provided with feet and having its intermediate portion formed with openings located near the sides and formed with slots leading from said openings out to the side edges, the body having a flat face formed with a pair of grooves extending from the openings to the upper

edge at points near the corners, the resultant thinning away of the material by the provision of the grooves providing sensitiveness for facilitating transmission of vibrations. ¹⁰

In testimony whereof I affix my signature.

ALBERTO M. ALVARADO.
